COMBINED TOP CAP AND BRACKET FOR A TRASH RECEPTACLE RACK

Tacko D. Alissandratos, U.S. 19, Live Oak, P.O. Box 606,
Tampa Springs, Fla. 33589

Filed July 12, 1968, Ser. No. 12,718

Term of patent 14 years

Int. Cl. D25—99

U.S. Cl. D28—1

FIG. 1 is a perspective view of the combined top cap and bracket for a trash receptacle rack of this invention.

FIG. 2 is a top plan view.

FIG. 3 is a perspective view of the combined top cap and bracket for a trash receptacle rack with double bracket arrangement.

FIG. 4 is a top plan view of the combined top cap and bracket for a trash receptacle rack of FIG. 3.

FIG. 5 is an end view of the combined top cap and bracket for a trash receptacle rack of FIG. 3.

FIG. 6 is a side view, partly in section of the combined cap and bracket for a trash receptacle rack of FIG. 3.

FIG. 7 is a view similar to FIG. 3 showing another form of the invention.

I claim:

The ornamental design for a combined top cap and bracket for a trash receptacle rack, as shown.
